CLAIM

The ornamental design for a shoe with sole having a transparent window and internal spheres, as shown and described.

DESCRIPTION

FIG. 1 is a bottom rear perspective view of a shoe with sole having a transparent window and internal spheres showing my new design;

FIG. 2 is a bottom view thereof;

FIG. 3 is a rear view thereof;

FIG. 4 is a side view thereof; and,

FIG. 5 is an opposite side view thereof.

The broken lines showing the remainder of the shoe are for environmental purposes only and form no part of the claimed design.

1 Claim, 5 Drawing Sheets
